US0D1080647S

(12) **United States Design Patent** (10) **Patent No.:** **US D1,080,647 S**
Probetts et al. (45) **Date of Patent:** **** Jun. 24, 2025**

(54) **DISPLAY SCREEN OR PORTION THEREOF WITH GRAPHICAL USER INTERFACE**

(71) Applicant: **Empower Annuity Insurance Company of America**, Greenwood Village, CO (US)

(72) Inventors: **Daryl Probetts**, Highlands Ranch, CO (US); **Sean Hough**, Thornton, CO (US)

(73) Assignee: **Empower Annuity Insurance Company of America**, Greenwood Village, CO (US)

(**) Term: **15 Years**

(21) Appl. No.: **29/871,476**

(22) Filed: **Feb. 21, 2023**

Related U.S. Application Data

(63) Continuation of application No. 16/418,679, filed on May 21, 2019, now Pat. No. 11,645,709.

CLAIM

The ornamental design for a display screen or portion thereof with graphical user interface as shown and described.

DESCRIPTION

The FIGURE is a front view of a display screen or portion thereof with graphical user interface showing our new design.

The outermost broken lines in the FIGURE show a display screen or portion thereof on a computing device and form no part of the claimed design. The other broken lines shown in the FIGURE are environment only and show portions of the graphical user interface that form no part of the claimed design.
